The white tube shown in Fig. **1.9** represents portions of the oxygen mask that form no part of the claimed design; Protection for color is not claimed. Fig. **1.1** is a front, left and bottom side perspective view of an oxygen mask showing our new design; Fig. **1.2** is a rear, right and bottom side perspective view thereof; Fig. **1.3** is a front elevation view thereof; Fig. **1.4** is a rear elevation view thereof; Fig. **1.5** is a left side elevation view thereof; Fig. **1.6** is a right side elevation view thereof; Fig. **1.7** is a top plan view thereof; Fig. **1.8** is a bottom plan view thereof; and Fig. **1.9** is a reference view showing the product in use state. Fig. **2.1** is a front, right and bottom side perspective view of an oxygen mask showing our new design; Fig. **2.2** is a rear, left and bottom side perspective view thereof; Fig. **2.3** is a front elevation view thereof; Fig. **2.4** is a rear elevation view thereof; Fig. **2.5** is a left side elevation view thereof; Fig. **2.6** is a right side elevation view thereof; Fig. **2.7** is a top plan view thereof; and Fig. **2.8** is a bottom plan view thereof. Fig.

3.1 is a front, right and bottom side perspective view of an oxygen mask showing our new design; Fig. **3.2** is a rear, left and bottom side perspective view thereof; Fig. **3.3** is a front elevation view thereof; Fig. **3.4** is a rear elevation view thereof; Fig. **3.5** is a left side elevation view thereof; Fig. **3.6** is a right side elevation view thereof; Fig. **3.7** is a top plan view thereof; and Fig. **3.8** is a bottom plan view thereof.
